UNITED STATES PATENT OFFICE.

EUGENE B. LAMB, OF PORTLAND, MAINE.

PAPERING-BOARD AND BUCKET-HOLDING ATTACHMENT THEREFOR.

No. 835,826.

Specification of Letters Patent.

Patented Nov. 13, 1906.

Application filed February 12, 1906. Serial No. 300,618.

To all whom it may concern:

Be it known that I, EUGENE B. LAMB, a citizen of the United States, residing at Portland, in the county of Cumberland and 5 State of Maine, have invented a new and useful Improvement in Papering-Boards and Bucket-Holding Attachments Therefor, of which the following is a specification.

My invention relates to improvements in 10 bucket-holding attachments for papering-boards and buckets therefor.

In the drawings herewith accompanying and making a part of this application, Figure 1 is an elevation of my improved device attached to a papering-board, the papering-board and bucket being in section. Fig. 2 is 15 a transverse sectional view of Fig. 1, taken on line $x-x$; and Fig. 3 is a plan view of the bucket.

20 Same letters of reference refer to like parts.

In said drawings, A represents a papering-board such as is usually employed by paper-hangers. Removably and revolvably secured thereto is a bracket comprising a horizontal 25 arm B, vertical arm C, and a curved brace D. The bracket is suspended from the bottom of the board. For convenience it may be suspended upon a bolt E, passing through the board and provided with a nut F, as seen 30 in Fig. 1. Thus constructed it will be apparent that the bracket may swing on the bolt F as a pivot, so as to bring the bracket and the bucket suspended therefrom, as hereinafter described, when not in use entirely 35 under the board, or when desired it may be turned on the pivot-bolt transversely of the board, bringing the bucket out from under the board. To the upright arm of the bracket the paste-bucket is secured in any 40 convenient manner.

I have illustrated in the drawings a means of supporting the paste-bucket which permits the bucket and the supporting means to be removed from the bracket. To do this, a 45 spring-clasp G is secured to the vertical arm of the bracket, the clasp being open at the top to give entrance to the bucket-supporting ring H. The bucket-supporting ring should preferably be of a diameter to support 50 the bucket at or above the middle thereof. The bucket I is provided on the inside near the top with loops J. A transverse bar K is supported in the bucket near the top. Turned-down ends L take into the loops J 55 and hold the bars in place, said bars being for the purpose of supporting the paste-

brush M when not in use. The bucket-supporting ring is detachable from the clasp G and can be inserted in a clasp N, secured to the brace D, said clasp N being arranged so 60 that when the bucket-supporting ring is placed therein the ring and the bracket lie in the same horizontal plane.

The advantages of my improved device are that the paste is always handy, it is not 65 liable to get upset, it can be turned at will under the board or to one side thereof, it is conveniently removed from the board and conveniently assembled with the board when not in use, and it is provided with means for 70 supporting the brush out of the paste when not in use.

The bucket may be used on either side of the bracket, the outside position being shown in dotted lines in the drawings. 75

Having thus described my invention and its use, I claim—

1. The combination with a papering-board of a bucket-supporting bracket revolvably secured to the under side thereof and 80 capable of revolving in a plane parallel with the under surface of said board.

2. The combination with a papering-board, of a bucket-supporting bracket secured to the under side thereof and a bucket- 85 holding ring secured to said bracket.

3. The combination with a papering-board, of a bucket-supporting bracket secured to the under side thereof and a bucket-holding ring removably secured to said 90 bracket.

4. The combination with a papering-board, of a bucket-supporting bracket, a bucket-supporting ring and two ring-supporting clasps, one adapted to support the 95 ring in a position substantially parallel with the board and the other in a position substantially in the plane of the bracket.

5. The combination with a papering-board, of a bracket revolvably secured thereto, a bucket-supporting ring on said bracket, and a paste-bucket having a brush-supporting bar extending transversely thereof near the top. 105

In testimony whereof I have signed my name to this specification, in presence of two subscribing witnesses, this 31st day of January, 1906.

EUGENE B. LAMB.

In presence of—

ELGIN C. VERRILL,
D. M. SANBORN.
